UNITED STATES PATENT OFFICE.

WILLIAM J. ELLIOTT AND IRVING M. MILLER, OF VALATIE, NEW YORK.

LATCH-OPENER ATTACHMENT FOR KNITTING-MACHINES.

SPECIFICATION forming part of Letters Patent No. 629,155, dated July 18, 1899.

Application filed December 5, 1898. Serial No. 698,278. (No model.)

To all whom it may concern:

Be it known that we, WILLIAM J. ELLIOTT and IRVING M. MILLER, citizens of the United States, residing at Valatie, in the county of Columbia and State of New York, have invented certain new and useful Improvements in Latch-Opener Attachments for Knitting-Machines; and we do hereby declare the following to be a full, clear, and exact description of the invention, such as will enable others skilled in the art to which it appertains to make and use the same.

This invention relates to dial knitting-machines and comprises an attachment whereby the latches of the dial-needles may be automatically opened or turned back when desired.

Heretofore it has been customary for the operative to employ her fingers to open the latches of the needles which are to receive the yarn at the beginning of the knitting operation and which may have become closed during the operation of hooking on the web or cuff. In the use of circular dial-machines this operation requires considerable time and care, for the reason that the operative must turn the machine a little at a time to throw back the latches with the fingers. Inasmuch as the dial is stationary and some of the needles will be on the opposite side of the frame from the operative it is necessary to either pass around the machine or to reach first on one side of the shaft and then on the other.

The object of this invention is the production of an attachment having a latch-opening finger normally out of the path of movement of the latches, but capable of being quickly placed in position, so that a single rotation of said attachment will open all of the latches which may be closed.

To this end the invention consists in the construction and combination of parts, as hereinafter described.

In the accompanying drawings, Figure 1 is a plan view of so much of a circular dial knitting-machine as is necessary to illustrate the invention. Fig. 2 represents a side elevation of the same. Fig. 3 represents a vertical section of the attachment on the line 3-3 of Fig. 1 on a somewhat enlarged scale.

Similar reference characters indicate the same parts throughout the several views.

The dial bed or plate *a* is provided with the usual grooves for the needles *b* and is held in stationary position while the needles thereof coöperate with the usual vertical needles (not shown) and relatively mounted and arranged, as shown in Patent No. 239,169 to W. D. Huse March 22, 1881. It is to be remarked here, however, that this invention is not limited to the knitting-machine shown in said patent, it being capable of use in connection with any knitting-machine employing horizontally-movable latch-needles. The shaft *c* is provided with the top plate *d*, to which the needle-operating cams are or may be attached in a manner such as shown in the above-mentioned patent.

With the form of machine mentioned and so far described the attachment forming the subject-matter of this invention is shown as carried by the top plate *d*. Said attachment comprises a bar or plate *1*, having elongated slots *2*, through which the screws *3* pass to secure the said bar to the top plate. The outer end of said bar is provided with a circular opening and is split, as indicated at *4*, a screw *5* working in the two sides of the bar on opposite sides of the split to enable the opening at the end of the bar to be contracted or clamped upon the barrel of the attachment, which will now be described.

A cylindrical barrel *6* is provided with a reduced lower end *7* to form a shoulder adapted to rest upon the surface of the bar *1* around the opening thereof.

Fitted to slide vertically within the barrel *6* is a rod *8*, having its lower end turned laterally, as indicated at *9*, to form the latch-opening finger, adapted to operate as herein-after described. The lower end of the barrel is provided with a vertical groove *10* to receive a pin *11*, projecting from the rod *8*, whereby the latter is prevented from turning on its axis. The vertical opening in the barrel is slightly enlarged above its lower end to form a shoulder *12*, on which rests a spring *13*. The upper end of the rod *8* is screw-threaded, as at *14*, to receive the sleeve *15*, provided with a milled rim *16*, and between the lower end of which and the shoulder *12* the spring *13* is confined. It will thus be understood that the spring *13* has a normal tendency to lift the rod *8* of the latch-opening finger

as far as the lower end of the barrel will permit, owing to the contact therewith of the lateral projection or finger 9. The rod 8 is of a length sufficient to extend somewhat above the upper end of the sleeve 15 and receives a set-nut 17.

Secured to the side of the barrel 6 is a spring 18, having a shoulder or lug 19, adapted to take over the edge of the milled rim 16 and provided with a finger-piece 20, by means of which the spring can be moved outward sufficiently to release the lug 19 from the milled rim 16.

When it is desired that the opener shall be moved to operative position, so that the sharp end of the finger 9 will be in a plane to cause any closed latches to ride thereover, the operative simply needs to press down upon the upper end of the rod 8 or the set-nut 17 thereon until the edge of the rim 16 is engaged by the spring-catch 18 19. To permit the finger to rise again to its normal position, the operative by means of the finger-piece 20 releases the spring-catch, and the spring 13 then immediately throws the rod 8 and its finger 9 upward to the position indicated by the dotted lines in Fig. 2.

The distance of the latch-opening finger 9 from the lower end of the barrel, and consequently its position relatively to the latch-needles when the opener is in operative position, may be adjusted by turning the sleeve 15 upon the screw-threaded portion 14 of the rod 8, thus changing the position of the milled rim 16 relatively to the latch-opening finger. The shoulder or lug 19 of the spring 18 is always in one position relatively to the barrel 6 and the top plate *d* of the machine, and consequently the vertical position of the rim 16 relatively to the finger 9 controls the position of the said finger 9 relatively to the latch-needles when the said milled rim is engaged by the spring-catch. The attachment therefore may be accurately adjusted in this respect, as will be readily understood.

The adjustment of the finger 9 in the direction in which it is desired to have it extend, so as to engage under the latches of the needles more or less distant from the hooks 50 thereof, is obtained by rotating the barrel within the opening of the bar or plate 1 and clamping it in its position by means of the screw 5. The elongated slots 2 in the bar or plate 1 permit of a radial adjustment, which is 55 also of use in adapting the attachment to different styles and sizes of knitting-machines.

Having thus described our invention and illustrated one mechanism for carrying it into effect, what we claim is—

60 1. A knitting-machine comprising in its

construction a series of latch-needles, a latch-opener therefor and a spring for normally retaining said opener out of the path of movement of the latches.

2. A knitting-machine comprising in its 65 construction a series of latch-needles, a latch-opener therefor, a spring for normally retaining said opener out of the path of movement of the latches, and means for adjusting the plane of the operative path of movement of 70 said opener.

3. A knitting-machine comprising in its construction a series of horizontally-movable dial-needles provided with latches, of a latch-opener therefor and a spring for normally retaining said opener above the plane of the 75 path of movement of said latches.

4. A knitting-machine comprising in its construction a series of latch-needles, a latch-opener movable into and out of position for 80 engaging the latches of said needles, a spring for throwing said opener to one position, and a catch for retaining it in the other position.

5. A knitting-machine attachment comprising a latch-opener, a guide therefor having 85 means for attaching it to a knitting-machine, a spring for holding the latch-opener in one position relatively to its guide, and a catch for holding said opener in the other position.

6. In a knitting-machine, the combination with a dial bed or plate and its needles, of the bar or plate 1 and a suitable support therefor, the barrel 6 mounted on the end of said bar, the rod 8 vertically movable in said barrel and provided with a latch-opening finger 9 at its lower end, and means within the control of the operative for adjusting the vertical position of the rod and its latch-opening finger.

7. In a knitting-machine, the combination with a dial bed or plate and its needles, of the bar or plate 1 and a suitable support therefor, the barrel 6 mounted on the end of said bar, the rod 8 vertically movable in said barrel and provided with a latch-opening finger 9 at its lower end, the sleeve 15 adjustably secured to the rod 8, the spring 13 bearing against the lower end of the sleeve, and a spring-catch adapted to engage the said sleeve 110 to hold it and the rod 8 and its latch-opener in depressed position.

In testimony whereof we affix our signatures in presence of two witnesses.
